UNITED STATES PATENT OFFICE.

DAVID BUTSON, OF WOLFORD, NORTH DAKOTA.

RURAL MAIL POST AND BOX.

1,368,110.

Specification of Letters Patent. Patented Feb. 8, 1921.

Application filed May 24, 1919. Serial No. 299,449.

To all whom it may concern:

Be it known that I, DAVID BUTSON, a citizen of the United States, residing at Wolford, in the county of Pierce and State of North Dakota, have invented new and useful Improvements in Rural Mail Posts and Boxes, of which the following is a specification.

This invention relates to mail boxes or receptacles and aims to provide an article of this character which is especially adapted for rural use.

The object of the invention is to provide a box which is simple and durable of construction and which will effectually protect its contents from the weather.

Another object is the provision of novel means for supporting the box so as to render its elevation convenient to a person on horse back or within a vehicle, or to persons standing upon the ground, the box being provided with a hinged cover or lid, which is controlled by the position of the box upon the support.

Other objects and advantages of the invention will appear as the following description is read in connection with the accompanying drawings.

In the drawings:

Figure 1 is a side elevation of a mail box and support constructed in accordance with the present invention.

Fig. 2 is a vertical sectional view with the lid in closed position.

Fig. 3 is a similar view showing the lid raised.

Referring to the drawings in detail, wherein like characters of reference denote corresponding parts, the support comprises a standard 10 of tubular construction, which has threadedly secured upon its upper end a rounded cap or closure 11.

Mounted for sliding movement upon the standard 10 is a bracket 12, carrying at one end a sleeve 13, having a sliding fit upon the standard. While the standard and sleeve are herein shown as circular in cross section, it is, of course, obvious that the shape may be varied, as desired.

Mounted upon the outer end of the bracket 12 is a box or receptacle 14, which is provided with a lid or cover 15 hinged along its rear edge, as shown at 16. The free end of the lid or cover 15 has connected thereto one end of a chain or other flexible connection 17, the opposite end of which is con-

nected to the cap 11. Secured to the bracket 12 is one end of a chain or cable 18, which passes upwardly through an opening 19 into the cap 11 and around a pulley 20, rotatably mounted within the said cap upon a spindle 21. The chain or cable 18 extends downwardly within the standard 10 and is provided with a counter-balance weight 22, the latter being so proportioned as to hold the bracket 12 in any adjusted position upon the standard.

When the bracket is raised to the position shown in Fig. 1, the lid of the box will be closed by its own weight, but when lowered to the position shown in Fig. 3, the said lid will be raised through the medium of the connection 17. By thus slidably mounting the box upon the standard, the latter will be in convenient position to be reached by a person on horse back or within a vehicle, but may be readily lowered to within reach of a person upon the ground. If desired, the chain or cable 23 may be secured to the outer end of the box 14 to aid in bringing it to a lowered position. The box may also be provided with a hasp padlock or with other locking means to prevent unauthorized opening. The usual indicator 24 may also be pivoted to the lid.

The invention is susceptible of various changes in its form, proportions and minor details of construction and the right is herein reserved to make such changes as properly fall within the scope of the appended claim.

Having described the invention, what is claimed is:

The combination with a hollow post or support, of a substantially U shaped elbow 95 positioned over the upper end of said post, a bracket, a sleeve carried by the bracket and mounted for sliding movement upon the post or support and engageable with the elbow to limit its upward movement, a receptacle secured upon the bracket, a hinged closure for the receptacle, a flexible connection between the post and closure and a flexible connection having one end secured to the bracket and passing into the hollow 105 post through the elbow and a weight slideable within the post and secured to the opposite end of the second mentioned flexible connection.

In testimony whereof I affix my signature. 110

DAVID BUTSON.
